CALCULATING MACHINE OF THE TEN
KEY TYPE

Ernst Valfrid Gustafsson, St. Essingen, and Gustaf Hilarius Hellgren, Malmo, Sweden, assignors to Aktiebolaget Facit, Atvidaberg, Sweden, a joint-stock company of Sweden

Application November 14, 1933, Serial No. 698,004
In Sweden November 22, 1932

35 Claims. (Cl. 235—79)

This invention relates to calculating machines, and particularly to machines of the ten key type.

Calculating machines are already known which are provided with a stationary selector and a shiftable carriage carrying an accumulator and a revolution counter. The machine according to the present invention differs from the type mentioned in that it includes a shiftable selector, a stationary accumulator and a stationary revolutions counter. This new calculating machine is characterized by the feature that the numeral keys are so combined with a device adapted to 10 actuate means for controlling the number of calculating operations, that the same are brought to cooperate with the said controlling means, whereby the numeral keys serve as a "multiplier" key.

According to a further feature of the present invention the multiplier, as also the multiplicand is set up or introduced by means of the same numeral keys into one and the same selector.

A further object of the invention is to provide an adjustable means which, when carrying out a multiplication operation is adapted to lock those calculating members which, though normally operating the wheels of the totalizer, correspond to the multiplier.

Further features of the invention will be apparent from the following description having reference to the accompanying drawings which illustrate by way of a preferred example of the invention a ten key calculating machine having a selector device which consists of a movable carriage or slide supporting movement limiting members or stop tongues. Similar reference characters are used to designate corresponding parts throughout the several views.

Figure 1 shows a vertical section through the main parts of the new calculating machine showing the numeral key "0" and the numeral key "5" together with pertaining mechanisms, the other numeral keys, the accumulator, the revolution counter and other devices not directly pertaining to the numeral keys having been left out for simplicity's sake.

Fig. 2 shows a vertical section through the machine including a starting key.

Fig. 3 shows a similar section as Fig. 2 with the starting key in a different position.

Fig. 4 shows a section through the machine showing the "multiplication" key and some wheels pertaining to the accumulator.

Fig. 5 shows a similar section as Fig. 4 but with the "multiplication" key in a different position, the calculating mechanism having been left out.

Fig. 6 shows a similar section as Fig. 5 but with the "naught" key in a different position.

Fig. 7 shows a section through the machine in a similar manner as in Fig. 1, it having been assumed that the "multiplication" key has been 5 actuated and the numeral key "5" has been depressed.

Fig. 8 shows a detail pertaining to the selector carriage advancing mechanism.

Fig. 9 shows a mechanism, partly in section, 10 for actuating the revolutions counter and a portion of the latter.

Fig. 10 shows the same mechanisms in a different position and further also the "multiplication" key.

Fig. 11 shows a general arrangement of the calculating machine in a plan view.

Fig. 12 shows a stop tongue such as arranged in the selector device.

The calculating machine as a whole is enclosed in a housing 1 and provided with the usual side walls and brackets in which the shafts are journaled and the supporting members are fixed. The machine as shown by way of example, is of the type in which the calculating or actuating members proper consist of toothed sectors 2 which are actuated each by its own spring 3 and are held in their normal or initial position by means of a rod 4 (Fig. 4) which extends through all toothed sectors and rests on one of their spokes 5. Each spring 3 is fixed at one end to its toothed sector 2 and with the other end wound round a rod 3b which is fixed to two plates 3c which are secured to the shaft 6. The sectors 2 may rock about the shaft 6 (compare Figs. 1 35 and 4). When the machine is operated the calculating sectors are set or swung in counter-clockwise direction by means of their springs 3 until a finger-like projection 7 on the sectors abuts against that stop tongue which in the particular instant has been actuated in the selector, for instance the tongue 8 corresponding to the numeral value "5" (Fig. 7). During its forward movement the toothed sector is not in engagement with any of the toothed wheels of the accumulator, but when the toothed sectors by means of the rod 4 are turned back to their initial position, the toothed wheel of the accumulator, that is to say either the toothed wheel 9 in addition operation or the toothed wheel 10 in subtraction operation, is simultaneously brought into engagement with its associated toothed sector 2. This movement of engagement will be more fully described later.

The selector mechanism

The selector which in the present case is displaceable (Fig. 1), comprises a carriage including an inner arcuated plate 11, an outer arcuated plate 12, side plates 13a and 13b (Fig. 11) and an angular piece 14. Between one leg 15 of the angular piece 14 and a prolongation of the inner plate 11 rollers 16 are mounted to run on a fixed rail 17. To the side plate 13a which connects the two plates 11 and 12, is fixed a bracket 18 having a notch 19 which is engaged by a rod 21 fixed to the main frame 20 of the machine. To the prolongation of the inner plate 11 is further fixed an angular piece 22 which is provided with notches 23 (Fig. 8). This angular piece is provided at its lower edge with locking teeth 24. In the plates 11 and 12 are arranged slots in which stop members or tongues, for instance 8, are displaceable. Each vertical row has ten such slots with a stop tongue in each of them, said tongues corresponding to the numerical values 0 to 9. The number of such rows in horizontal direction depends on the capacity of the calculating machine. Each stop tongue (Fig. 12) has an opening 25 through which the finger-like projection 7 on the toothed sectors can pass in those tongues which have not been pressed out of the selector. When such stop tongue is partly pressed out the finger-like projection 7 abuts that portion 26 of the tongue, which is situated radially inwardly of the opening 25. The stop tongue is provided at its upper end 27 which is bent at an angle, with a number, for instance with the number 5, and this number will become visible, upon the respective tongue having been actuated, through an opening 28 arranged in the front wall of the machine housing. The stop tongue is further provided with a shoulder 29 with which the same normally rest on the inner plate 11 of the selector. These stop tongues are pressed out of the selector to a certain extent of their length by means of numeral keys. For this purpose each numeral key consists of an arm 30 bent at several angles and pivoted on a rod 31 (Fig. 1). The arm 30 has at one end the form of a hammer 32 by means of which the stop tongue is partly pressed out. The other end of the arm 30 is pivoted at 33 to a stem 34 extending upwardly and provided at its upper end with a key knob 35. The arm which is pivoted to the key stem has a prolongation 30b which is influenced by a spring 30c which is fixed with one end to the end of said prolongation and with the other end to the frame of the machine. Corresponding parts belonging to the "naught" key are designated with the same reference characters but with the addition of the letter "a".

The mechanism for setting the machine for multiplication

Pivoted to the shaft 31 is further a bow 36 common for all numeral keys and having an arm 36b which at its free end has a projection 37 adapted to cooperate with a carriage advancing mechanism (Fig. 8) to be described later. In the neighbourhood of the pivot 33 of the key stem each key arm is provided with a projection 38 having a recess 39 whereby a hook is formed. This hook is adapted to cooperate with a rib 40 on an arm 41 which is pivoted about a shaft 42. Each key arm 30 is further provided with a lateral projection 43 adapted to cooperate with an abutment in form of a finger 44. All these fingers 75 are securely fixed to the shaft 42. To this shaft

42 is further fixed a toothed sector 45 having a stud 46 to cooperate with the arm 41. The toothed sector is influenced by a spring 47 which tends to turn the toothed sector in clock-wise direction. Normally cooperating with the toothed sector is a locking pawl or dog 48 (Fig. 4) which by means of a spring 49 is kept in engagement with the teeth on the said sector. The locking dog is pivoted on a stud 50 fixed to one side wall of the machine. This locking dog has a flange 51 to cooperate with a hook 52 (Figs. 2 and 3) which is operatively connected with a "starting" key 83, and also to cooperate with a hook 66 which is controlled by the "multiplication" key and by the bow 36 common to all numeral keys. The "starting" key also has a lateral projection 43b which cooperates with a finger 44b fixed to the shaft 42. This finger 44b and the projection 43b permit a movement of the toothed sector corresponding to one of its teeth. When the "starting" key is actuated the locking dog 48 is lifted out of engagement with the toothed sector 45, so that this latter actuated by its spring 47 turns in clockwise direction until the pertaining finger 44b abuts against the latter projection 43b on the depressed "starting" key. The toothed sector 45 is moved back step by step in counter-clockwise direction through the intermediary of a mechanism now to be described. About the shaft 53 is rotatably mounted a member 54 having three arms 55, 56 and 57. The free end of the arm 57 is in the path of movement of a roller 59 mounted on a rotatable disk 58, and by means of said roller the member 54 thus receives an oscillating movement when the disk 58 rotates. This will be described later. The free end of the arm 56 is pivoted as indicated at 60, to a feeding or restoring member 61. This restoring member is influenced by a spring 62. One arm 63 of the said restoring member rests normally on a pin 64 fixed to one wall of the machine. The restoring member is further provided with a projection 65 which normally rests on the arm 56. The member 61 and the arm 56 thus form a toggle joint which is kept in the position shown in Fig. 1 by means of the spring 62 and the projection 65 resting on the arm 56. When the arm 57 of the member 54 is actuated by the roller 59 the toggle joint is straightened, so that the member 61 engages with the toothed sector 45 and pushes this latter back one step at a time in counter-clockwise direction. When the parts occupy the position shown in Fig. 1, the member 61 is, however, situated out of the path of the teeth on the toothed sector 45, so that this latter when being set can move past the feeding member 61 in correspondence to the depressed numeral key or the "starting" key. The arm 55 has a lateral projection 67 to cooperate with one arm 68 of a double-armed lever 68, 70 (Fig. 7) which is controlled by the "multiplication" key. This lever is pivoted about a stud 69. The free end of the other arm 70 cooperates with a stud 71 fixed to the stem 34a of the "naught" key. Said lever is influenced by a spring 72 which tends to turn the same in clockwise direction. To the free end of the arm 68 is pivoted at 73 a member 74 which carries the hook 66 (Fig. 4). This member 74 has a prolongation extending downwardly and having a slot 76 which is engaged by a pin 77 fixed to the bow 36 common to all numeral keys. The arm 68 has a lateral projection 78 which normally, that is to say when the "multiplication" key occupies its normal lifted-up position, rests on an arm 79 (Fig. 4) which is pivoted at 80 to

the stem 81 of the "multiplication" key. The arm 79 is pivoted about the stud 82 and is influenced by a spring 83 which tends to hold the "multiplication" key in lifted-up position. The stem 81 of this key and the arm 79 are interconnected by a spring 84 which tends to hold the lower end of this stem in engagement with the bracket 85. At the lower end this stem has a catch shoulder 86 which engages with the bracket 85 when the key is pressed down. (Fig. 5.) At its upper end this stem 81 is provided with a projection 87 which limits the movement of this stem in upward direction.

The hook 52 which also is adapted to cooperate with the flange 51 of the locking dog 48 (Figs. 2 and 3) is pivoted at 89a to an arm 89 pertaining to a "starting" key. The arm 89 is pivoted about a stud 90 and at 91 pivotally connected with the stem 92 of the "starting" key, which stem supports at its upper free end a key head 93. This key is kept in its normal lifted-up position by means of a spring 92b. The hook 52 is influenced by a spring 94 which tends to turn the hook in counter-clockwise direction. This movement is limited by a pin 95 fixed to the arm 89 and also by a projection 96 on the hook 52.

The arm 41 which may rock about the shaft 42 (Figs. 1, 2 and 3) is integral with an arm 97 which has a shoulder 98 and a prolongation 99. The shoulder 98 cooperates with a stud 100 fixed to one arm 101 of a member 104 provided with three arms 101, 102 and 103 and pivoted about a shaft 105. The free end of the arm 102 is adapted to cooperate with the notches 23 of the angular piece 22 which is fixed to the selector. The arm 103 supports a contact member 106 which cooperates with a contact member 107 fixed to the main frame of the machine. These contact members are connected by means of leads 108 and 109 to the circuit of the driving motor of the machine. The arm 103 further has a lateral projection 110 which normally rests on a bell crank lever 111, 112 which is pivoted at 113 to the disk 58 which is securely fixed to the main shaft 114 of the calculating machine. The arm 112 of the bell crank lever is influenced by a spring 115 which tends to turn the bell crank lever in counter-clockwise direction. The arm 112 is further provided with a hook 116 which is adapted to cooperate with teeth 117 on a clutch device 118. This clutch device is securely fixed to the shaft 119 of the driving motor which rotates in the direction of the arrow 120. The main shaft 114 of the machine and the shaft 119 of the motor are separated from each other but arranged in axial alignment relative each other.

The revolutions counter

The revolutions counter C and pertaining mechanisms are shown in Figs. 9 and 10 in two different positions of operation.

The quotient register differs from the usual counting devices in that each numeral drum has an individual feeding mechanism that is adapted to be operated from the main shaft 114.

The numerals drums of the quotient register are each provided with a feeding mechanism, and the particular numeral drum which is to register the number of rotations of the main shaft during any one operation is controlled by a coupling mechanism that is adjusted along the series of feeding mechanisms by the movement of the selector carriage. The details of this feeding mechanism will be apparent from the following:

To the main shaft 114 of the calculating machine is fixed a cam disk 131 which cooperates with two rollers 132 and 133 mounted on the bifurcated portion on one arm 134 of a double-armed lever 134, 135 which is pivoted about a rod 136. The free end of the arm 135 is pivoted to a bar or link 137 which at its free end is pivoted to a member 138 which is common to all digital orders of the revolutions counter and may be rocked about a rod 139. The member 138 has an upper and a lower bent edge 140 and 141, respectively, which edges are adapted alternately to cooperate with a plurality of feeding members 142, 143 one for each of the denominational orders of the revolutions counter. Each feeding member 142 is adapted to cooperate with its pertaining toothed wheel 144, which is securely fixed to a numeral drum 145 constituting one denominational order of the revolutions counter which in its entirety is designated C (Fig. 11). The feeding member 143 is adapted to cooperate with a toothed wheel 146 which is constantly in engagement with the toothed wheel 144. Both feeding members 142 and 143 are made integral and adapted to be rocked about a stationary rod 141. The lower feeding member 143 has an elongated slot 148 by means of which it is able to slide on a pin 150 fixed to a swing rod 149 the lower arm of which is bent at an angle. Each swing rod 149 is pivoted at its upper end to member 142 such as indicated at 151 and is pivoted at its lower end at 152 to one of a plurality of arms 153 which may be rocked about a shaft 154. Each arm 153 has its free end bent twice to form a U-shaped member 155 which supports a spindle 156 carrying a control member 157 which is united with a tens carrying hook 158. This latter is adapted to cooperate with a corresponding projection 159 on the hub of the toothed wheel 146. Each control member 157 is influenced by a spring 157a and each swing rod 149 is influenced by a spring 149a. Below all the arms 153 there are two arms 169 (161) which are pivoted about a shaft 162 and are united with each other by means of a bridge piece 163. The free ends of these arms support a rod 164 which supports a carrying or coupling member 165 of a width corresponding to one denominational order of the revolutions counter. This coupling member 165 surrounds the rod 164 not entirely but only with something more than half the circumference, so that the member 165 cannot fall off the rod, while on the other hand the upper surface of the rod is left entirely free, so that this surface may directly cooperate with the U-shaped portion 155 of all arms 153. To the rod 164 is further pivoted a link 166, the other end of which is pivoted to a crank pin 167 fixed to an arm 167b which is attached to the shaft 6. Each control member 157 has a shoulder 168 which normally rests on a rail 169 (Fig. 10) and further a recess 170, which in another position of the control member rides on said rail 169, and finally a recess 170a which is adapted to cooperate with a projection 171 of the coupling member 165. A shoulder screw 172 is screwed from underneath into the coupling member 165 and its shoulder engages in a slot 173 in a horizontal arm 174, the other end of which is pivoted by means of a horizontally arranged pin 175 to a blocking device 303, 304, 304a, 305. This locking device is axially displaceable on a rock shaft 176 provided with an axial groove 177 into which extends a peg 178 integral with the member 303. This latter member consists of two arms which are interconnected by a bridge 304 having a tooth 305 adapted to engage 75

one of the teeth 179 arranged on the upper end of the radial inner plate 11 of the selector carriage. The bridge 304 is bent upwardly to form a rail 304a which is adapted under certain circumstances, to be described later, to engage a notch 7a in the members 7 (Fig. 1). To the rock shaft 176 is fixed an arm 180, the free end of which is pivoted to a rod 181, the other end of which is pivoted to the arm 79 pertaining to the 10 "multiplication" key 88.

The accumulator mechanism

Each plate 3c (Fig. 10) constitutes one arm of a double-armed lever 3c, 182 (182a). Between the arms 182 and (182a) is fixed the rod 4 which extends through the toothed sectors 2 (compare Fig. 4). To the arm 182 is pivoted at 183 a link 184 which at its other end is pivoted at 185 to an arm 186 which by means of a key is fixed to the main shaft 114. To this shaft is further fixed a cam disk 187 which cooperates with two rollers 188 and 189 mounted on the bifurcated end 190 of an arm 191 constituting one arm of a bell crank lever 191, 193 pivoted about a shaft 192. The bell crank lever is fixed to a sleeve 194 and at the other end of this sleeve is fixed a companion arm (195) similar to the arm 193. Between the arm 193 and its companion (195) extends a spindle 196 about which are pivoted two plates 197 (198) which between themselves support two minor spindles 199 and 200. The spindle 199 supports the toothed wheels 10 and the numeral drums 201 made integral with the latter, while the spindle 200 supports the toothed wheel 9 which permanently engages the toothed wheels 10. This arrangement with the rock plates 197 and (198) together with the gear wheels has been made in order to render possible the utilization of the calculating machine for carrying out 40 addition as well as subtraction and multiplication or division, in that the said plates may be rocked about the spindle 196 by means of a rod system 203, 204 which may be actuated by a key or keys in a manner known per se, and therefore 45 these details have not been shown or described in this connection. It may be assumed that in addition or multiplication operations the toothed wheels 9 are to be brought into engagement with the toothed sectors 2, so that the numeral drums 201 will be turned in the direction of the arrow 205 during the said calculating operation. For 50 subtraction, the linkage system 203, 204 is actuated by subtraction key 88 to rock the plates 197, 198 into position for the engagement of subtraction wheels 10 with the toothed sectors 2 when the lever system 191—195 is actuated by the cam 187 on shaft 114.

The selector adjusting mechanism

60 The mechanism for advancing the selector carriage step by step is shown in Fig. 8. As pointed out above, the radially inner plate 11 of the selector frame is provided at its lower portion with teeth 24. On the rail or bar 17 which extends 65 through the entire length of the machine and which is supported by the uprights 206 and 207, is fixed a stop 208 for a bar 209 displaceable in horizontal direction. This bar is pivoted to two arms 210 and 211 which are pivoted to the uprights 206 and 207, respectively. The bar 209 has 70 two projections 212 and 213 extending downwardly, and between the projection 213 and the rail 17 is fixed a spring 215 under tension which tends to displace the bar 209 to the right (Fig. 8 75 which shows the parts seen from the front of the

machine). To the bar 209 is pivoted at 216 a double pawl escapement 211, 218, one pawl 217 of which is connected with the projection 212 by means of a tension spring 214 which tends to press the other pawl 218 of the escapement into engagement with the teeth 24. The movement caused by this spring 214 is limited by a stop 219 mounted on the bar 209. Near the pawl 217 the escapement is provided with a projection 220 which is located above the projection 21 on the bridge 36 (Fig. 1). The selector carriage is influenced by a spring 221 which tends to pull the same in the direction of the arrow 222. It is to be noted that the spring 221 is considerably stronger than the spring 215, so that the selector carriage and the other parts normally are kept in the position shown in Fig. 8.

The mode of operation of the various mechanisms will now be described and in order to obtain a general view of the function of the machine during the operations, at first the function of the calculating mechanism and that of the revolutions counter will be explained before the mode of operation of the various keys are described.

The function of the calculating mechanism

When the main shaft 114 of the machine is coupled in the manner to be described later to the motor shaft 119, the arm 186 (Fig. 4) is first rotated 180° in the direction of the arrow 120, whereby the arms 182 (182a) are rocked together with the shaft 6 in counter-clockwise direction. As a result of this rocking movement the rod 4 releases the toothed sectors 2 which, influenced by their springs 3, also rotate in counter-clockwise direction until the finger-like projections 7 are stopped by the projected stop tongue or tongues which in the particular case shown in Fig. 7 is the tongue 8 corresponding to the numeral value "5". In those orders of the accumulator, generally designated A (Fig. 11), which are located to the left of the first order of the selector the toothed sectors 2 cannot move, because the selector carries for this purpose a locking device, for instance a plate 225 which normally engages with the notches 7a and which during the displacement of the selector carriage step by step is drawn out of these recesses, whereby the respective toothed sectors 2 are released. When thereafter the shaft 114 is turned the second 180°, the arms 182 (182a) are rocked in clockwise direction and thereby the toothed sectors previously set are restored by the rod 4 to the initial position. During the forward movement of the toothed sectors, that is to say in counter-clockwise direction, the cam disk 187 has such position relative to the rollers 188 and 189 and thus relative to the bell crank lever 191, 193 (195) that the toothed wheels 9 and 10 are out of engagement with the toothed sectors 2, while during the second half revolution of the main shaft 114 the cam disk 187 has such position that one of the said toothed wheels engages with the toothed sector 2. Registration is thus effected in the accumulator while the toothed sectors 2 are restored to initial position. The accumulator A is naturally provided with ten-carrying means which however form no part of the present invention and therefore have not been shown or described.

The function of the revolution counter

Under normal conditions, that is to say when carrying out an addition, the revolutions counter is influenced by the system 131—141 in collabora-

tion with the system 153—167 (Figs. 9 and 10). When the main shaft 114 rotates one revolution only, as is the case when carrying out a single adding operation, the member 138 has rocked once about the shaft 139 to and fro. Simultaneously the shaft 6 is oscillated to and fro as explained above in connection with the function of the accumulator, whereby and through the intermediary of the link 166 the coupling member 165 is moved up and down along a circular arc with the shaft 162 as centre of rotation.

As stated above, for each denominational order of the revolutions counter there is an arm 153 with a control member 157, further a member 142, 15 143. The coupling member 165, which, as stated above, is of a width corresponding to one denominational order of the revolutions counter, is axially displaceable on the shaft 164, together with the rod 164 and the blocking member 303, 20 and therefore it can cooperate with only one denominational order at a time. Normally all arms 153 are in a raised position, such as shown in Figure 10, in which the shoulder 168 of the member 157 rests on the rail 169. In this position, the U-shaped portion 155 of all arms 153 is a short distance above the rod 164 and the member 165 is able to pass through the recess 170a in all members 157. When the shaft 6 is oscillated and the arm 167b is moved down and then up again, 25 the rod 164 does not influence the U-shaped portion of the arms 153. However, in that denominational order of the revolutions counter in which the coupling member 165, 171 is situated, the numeral wheel will be moved forward a step 30 in the following manner: At the beginning of a cycle (one revolution of the shaft 114) the cam disk 131 presses the roller 133 to the right (Fig. 10) so that the upper arm of the double-armed lever 134, 135 will be rocked to the left. The link 40 137 rocks the member 138 about the rod 139 in clockwise direction, whereby the feeding pawl 143 is rocked into the space between two adjacent teeth of the wheel 146. Shortly thereafter the shaft 6 is rocked in clockwise direction thereby 45 drawing the link 166, the rod 164 and the member 165 downwards. The member 165 rocks the member 157 in counter-clockwise direction so that its shoulder 168 leaves the rail 169 and the spring 157a draws the member 157 together with the pertaining arm 153, the rod 149 and the feeding pawls 142, 143 downwards, all parts now occupying the position shown in Fig. 9, in which the wheel 146 thus has been rotated half a step in clockwise direction, the wheel 144 having simultaneously been rotated half a step in opposite direction. At the beginning of the second half-cycle the cam disk 131 presses the roller 132 to the left and therefore the upper arm 135, the link 137 and the lower part of the member 138 move to the 50 right. On account of the angular shape of the lower part of the rod 149 and due to the action of the spring 149a the feeding member 142, 143 will be swung in counter-clockwise direction about the rod 147 and the pawl 142 will enter a 55 space between two adjacent teeth of the wheel 144. Shortly thereafter the link 166 is lifted again, whereby the rod 164, the arm 153, the rod 149 and the pawl 142 are lifted, so that the wheel 144 is rotated half a step in the same direction 60 as before, i. e. counter-clockwise, thus altogether one step. Upon the rod 164 having lifted the arm 153 so much that the member 157 with its shoulder 168 again rides on the rail 169, it returns to its initial position, such as shown in 65 Fig. 10.

The action of the tens-transfer mechanism of this revolutions counter is similar to that of the mechanism just described. When for instance the numeral wheel in that denominational order in which the member 165, 171 stands, is pushed forwards from 9 to about half-way between 9 and 0, the projection 159 presses the transfer hook 158 of the next higher order outwardly, whereby the shoulder 168 of the member 157 will leave the rail 169 and the arm 153 falls upon the shaft 164. At the same time, the pertaining pawl 143 has pushed the wheel 146 of the next higher order half a step in clockwise direction (see Fig. 9). During the second half-cycle, the first-named numeral wheel is moved from halfway between 9 and 0 to 0, and therefore the said projection 159 is moved out of the way of the transfer hook 158, so that the wheel 144 of the next higher order can be rotated the second half step, when the link 166 with the rod 164 lifts the arms 153 which 20 previously had fallen down.

Setting the machine for adding

When a numeral key is pressed down during an adding operation, that is to say when neither 25 the "multiplication" key nor the "starting" key has been depressed, a stop tongue is displaced by the hammer 32 out of selector to a certain portion of its length and this stop tongue engages, simultaneously as the selector carriage is moved 30 to the left as above explained, with a slot 8a in a plate 8b which is mounted in the opening 28 of the housing 1 (Figs. 1, 7 and 11). When depressing a numeral key the parts with the exception of said numeral key and the common bow 35 36 maintain the positions shown in Figs. 1, 2, and 4. When thereafter the numeral key is again released, the respective numerical value has been introduced into the selector, and in order to now transfer this numerical value to the accumulator 40 A, the starting key 93 is pressed down from the position shown in Fig. 2 to the position shown in Fig. 3. Hereby the following operation is effected: The arm 89 of the starting key is rocked about the shaft 90 45 in counter-clockwise direction and the hook 52 influenced by its spring 94 follows this movement. The hook 52 in its turn turns the locking dog 48 in clockwise direction against the influence of its spring 49. The spring 94 is stronger than the spring 49. By this movement of the locking dog 48 the toothed sector 45 is released which influenced by its spring 47 turns in clockwise direction together with the shaft 42 and the finger 44b fixed thereto together with all other 50 fingers 44 (Fig. 1). As indicated above, the finger 44b is arranged in the path of movement of the projection 43b on the arm 89 of the "starting" key, and the distance between the finger 44b and the projection 43b is such that the toothed 55 sector 45 only can turn one step corresponding to a pitch of the toothed sector 45. The pin 46 fixed to the toothed sector has simultaneously released the arm 41 having the rib 40, and this arm which is made integral with the arm 97 is 60 turned, influenced by the spring 97b, in clockwise direction. Certain of the ports are locked against accidental or inadvertent movement by displacing the rib 40 backwards (to the right as shown in Fig. 3). In the first place, the "starting" 65 key is blocked from a return upwards by the spring 92b, for the reason that the hook 38b is located below the rib 40. Furthermore, this displacement of the rib 40 brings it into engagement with the recess 39 in each one of the numeral 70 75

keys and in the "multiplication" key thus preventing the depressing of any one of these keys. By turning the arm 97 in clockwise direction the three-armed member 101, 102, 103 has been turned in counter-clockwise direction through the intermediary of the shoulder 98 and the pin 100. The arm 102 engages a notch 23 in the selector frame and locks this latter in the position it occupies at that particular instant. The arm 103 closes at 106 and 107 (Fig. 3) the circuit for the driving motor of the calculating machine and its projection 110 simultaneously releases the coupling member 111, 112, 116. The motor thus is started and its shaft 119 together with the clutch device 118 rotates. The coupling member 112 is turned by the spring 115 about the stud 113 into the path of movement of the 117 of the clutch device 118, and as soon as the hook 116 has come into engagement with one of said teeth 117, the disk 58 and thus the machine shaft 114 are carried along and rotate in the direction of the arrow 120. When the disk 58 has completed about $\frac{3}{4}$ of one revolution the roller 59 influences the arm 57 and presses the latter together with the arms 55 and 56 in clockwise direction, thereby carrying along the feeding or restoring member 61 which is influenced by its spring 62 and engages with the toothed sector 45 and pushes this latter back one step in counter-clockwise direction. By this movement of the toothed sector the following operation comes about: The pin 46 presses the arm 41 one step to the left, whereby the rib 40 releases the "starting" key 93 which is lifted by its spring 92b to its normal position. Hereby the hook 52 releases the locking dog 48 which again snaps into the teeth of the toothed sector 45, so that this latter is held in this new position, that is to say in the present case in its original initial position. Together with the turning of the arm 41 also the shaft 42 and thus the arm 97 have been turned in the same direction, and this arm 97 has through the intermediary of the spring 99b turned the three-armed member 101, 102, 103 in clockwise direction. By this means the circuit for the motor is interrupted at 106, 107, so that the motor immediately thereafter comes to a standstill. Simultaneously the projection 110 has been moved into the path of movement of the coupling hook 112, so that this latter is pressed back to the position shown in Figs. 1 and 2, and further the disk 58 and thus the main shaft 114 of the machine is stopped in the position as shown. In order to provide place for the projection 110, when the arm 97 turns the member 101, 102, 103, the disk 58 is provided with a recess 58b in front of the coupling member 112.

The main shaft of the machine has thus carried out one revolution and during this revolution the numerical value introduced into the selector has been transferred to the accumulator A and the revolutions counter C is caused to register "one". The rest of the parts occupy again the position shown in Figs. 1, 2, and 4. Upon the selector carriage having been returned to the initial position and the partly pressed out tongues 8 having simultaneously and automatically also been pressed back to their initial positions, the selector is ready for having a new item set up in the same.

Setting the machine for multiplication

When the machine is to be utilized for carrying out a multiplication the same numeral keys 75 which are used for setting up the multiplicand

in the selector will also be used for determining the multiplier. In this case the mode of operation of the machine is as follows: Upon an item (a multiplicand) having been set up in the selector in the manner just described, the "multiplication" key 88 is depressed, which is kept in this pressed-down position by means of the catch shoulder 86 and the bracket 85 against the action of the spring 83 (Figs. 4 and 5). When pressing down this key 88 the arm 79 has been turned in counter-clockwise direction, whereby the following parts are influenced: the lever 68-70 is released and is turned by its spring 72 in clockwise direction, in that its projection 78 follows the movement of the arm 79. By this means the member 74 with the hook 66 has been moved downwards, the portion 75 thereof with its slot 76 having slid along the pin 77 on the bow 36 of the numeral keys. The hook 66 is now situated in front of the projection 51 of the locking dog 48. The arm 79 also influences the rod 181, whereby the rock shaft 176 is turned in counter-clockwise direction, so that the rail 304a on the bridge 303 is located in alignment with the notches 7a in the finger-like projections 7 of the toothed sectors 2. Simultaneously the tooth 305 has been brought into engagement with a notch 179 in the selector, so that the member 303 is locked to the selector. This has the result that during the lateral displacement of the selector carriage, following thereafter, also the coupling member 165 follows in axial direction, so that the revolutions counter will be caused to register the number of revolutions in the particular denominational order. The rest of the parts with the exception of the lever 68, 70 occupy until further the positions shown in Fig. 1. When now a numeral key, for instance the key 35 corresponding to the numerical value "5", is pressed down the following occurs:—The bow 36 common to all numeral keys is turned in counter-clockwise direction, and this time the locking dog 48 is not influenced by the hook 52, as is the case when depressing the "starting" key, but is influenced by the hook 66 through intermediary of the pin 77 and the part 75 (Fig. 7). Thereafter the toothed sector 45 is turned, influenced by its spring 47, in clockwise direction and by this means the shaft 42 and the fingers 44 fixed thereto are also turned in clockwise direction. The particular finger 44 which corresponds to the selected numeral value "5" will rest against the projection 43 on the arm 30 of the numeral key in question, allowing the toothed sector 45 to rock through an angle corresponding to five teeth. Simultaneously the arm 41 is released by the pin 46 and is turned together with the arm 97 to the position shown in Fig. 7, whereby the motor is started in the manner above described and the arm 102 locks the selector carriage, in that it engages a notch 23 of the latter. The influence of the projection 37 on the escapement 217, 218 (Fig. 8) does not in this case result in a displacement of the selector carriage, because the arm 102 engages the notch 23 at the same time as the dog 218 is pressed out of engagement with a tooth 24. On account of the influence of the spring 215 the bar 209 with the pawls 217, 218 are moved somewhat to the right, so that later on, when the arm 102 again releases the selector carriage this latter is displaced a step to the left (Fig. 8). As indicated above, each numeral key has a projection 38 and this projection is located below the rib 40, so that the key 35 cannot move upwards

until the arm 41 has again been turned to its initial position. This arm 41 however rests in the position shown in Fig. 7 on account of the influence of the spring 91b, until the toothed sector with its spring 46 has been turned five steps in counter-clockwise direction and thereby has pressed the arm 41 to the position shown in Fig. 1. The toothed sector 45 is moved back to the initial position in a similar manner as explained above in connection with the single adding operation, but in this case step by step five times through the intermediary of the roller 59, the member 55, 56, 57 and the restoring member 61. Each time the roller 59 influences the arm 57, the toothed sector is moved a step in counter-clockwise direction. As stated above the arm 55 has a projection 67 which engages the arm 68 from underneath (Figs. 1 and 7). This projection has the purpose to lift the arm 68 and thus 20 the hook 66 immediately upon the toothed sector having been released in order to release the locking dog 48, so that this latter may again take up its function. When the roller 59 actuates the arm 57 the first time, the arm 68 is lifted, so that 25 the locking dog 48, influenced by its spring 49, again engages with the toothed sector 45 before the restoring member 61 has completed its stroke. During the actuations of the arm by the roller 59 following thereafter, the hook 66 is moved 30 only in the direction towards the projection 51 without, however, bringing the locking dog 48 out of engagement with the toothed sector 45. Upon the toothed sector in this manner having been moved back five steps to the initial position, the 35 pin 46 brings the arm 41 along to the left and thereby the clutch device 116, 117 is opened in the manner described above; further, the arm 102 releases the selector carriage, the rib 40 releases the key 35 and the bow 36 releases with its portion 37 the escapement 217, 218, so that 40 the selector carriage influenced by its spring 221 is displaced as above indicated one step to the left and the motor is stopped. During these five revolutions of the main shaft of the machine the item set up in the selector has thus been transferred five times to the accumulator A, and this in those orders which are situated at the extreme right of the accumulator. Further the multiplier, namely the item "5", has been introduced into the revolutions counter in its first order, that is to say in the order at the extreme 45 right of Fig. 11. At the end of this multiplication operation the selector carriage has been displaced, as indicated above, one step to the left (Fig. 11) and this displacement is also carried out by the member 303, inasmuch as this member by depressing the "multiplication" key has been locked to the selector (Fig. 5. See also applicants' U. S. Patent 1,930,475). The "multiplication" key 50 remains in the pressed-down position but may be released in usual manner by at first pressing the button 88 of the key somewhat back in order to release the catch shoulder 86 from the bracket 85 and then releasing the key.

55 In case the multiplier consists of several figures, for instance "35", a multiplication is carried out in known manner at first with the unit item "5" and thereafter with the tens item "3". As a continuation to the example above referred 60 to it shall now be assumed that the item set up in the selector also is to be multiplied with a tens item "3", that is to say with thirty. The selector and the member 303 are situated one step to the left after the first multiplication operation, which means that the member 303 with

its rail 304a locks the prolongation 7 pertaining to the first denominational order of the accumulator (Fig. 5). At the same time the coupling member 165 lies in the second denominational order of the revolutions counter counted from the right. If now the numeral key corresponding to the value "3" is depressed and under the supposition that the "multiplication" key 88 is still in its pressed-down position, the above described multiplication operation will be repeated with the 10 difference that this time the toothed sector 45 is turned three steps only to the right for the reason that the finger 44 abuts against the projection 43 on the numeral key "3". By this turning of the toothed sector the pin 46 is removed from 15 the arm 41, so that the motor is started in the manner above described, which has the result that the toothed sector is turned back three steps to the initial position. During these three steps, that is to say, during three revolutions of 20 the main shaft 114 of the machine, the item set up in the selector has been transferred three times to the accumulator, namely in those denominational orders which are located to the left of its first denominational order. At the 25 same time the figure "3" has been set up in the revolutions counter in its second order counted from the right. The accumulator thus indicates the result of the product between the multiplicand and the multiplier and the revolutions counter 30 indicates the multiplier, that is to say "35". After this multiplication operation the selector carriage is again moved a step to the left in which movement follows the member 303.

When in adding operation the item "0" is set up 35 in the selector, the bow 36 is actuated in the same manner as when depressing any of the other numeral keys, and the tongue corresponding to the figure "0" is partly pressed out of the selector by means of the hammer 32a. At the same 40 time the selector carriage is displaced one step to the left through the intermediary of the member 37 connected with the bow 36. When carrying out a multiplication, the accumulator must not be influenced, as is well known, when the 45 multiplier contains the figure "0", for instance in case the multiplier is constituted by the figure "305". Upon the multiplication having been carried out in the manner above stated for the item "5" and the selector carriage has been displaced one step to the left, and if thereafter the "naught" key 35a is pressed down, the selector carriage only is to be displaced a further step to the left without the motor being started or without any item being registered. For this purpose 55 the arm 70 of the lever 68 extends below the pin 71 on the stem 34a of the "naught" key when the "multiplication" key 88 is pressed down (Fig. 6). In this position the hook 66 is situated a minor distance in front of the projection 51 on 60 the locking dog 48 which engages the toothed sector 45 (compare Fig. 2). As explained above the hook 66 will when depressing a numeral key, that is to say one of the keys corresponding to the figures "1" to "9", lift the locking dog 48 out of engagement with the toothed sector 45. However, when depressing the "naught" key 35a the lever 68, 70 is turned about the stud 69, which means that the hook 66 is lifted above the projection 51 of the locking dog 48, so that when 65 the bow 36 is actuated the hook 66 through the intermediary of the pin 71 swings past the projection 51 without bringing the locking dog 48 out of engagement with the toothed sector 45.

Setting the machine for subtracting

When a subtraction is to be carried out the base figure is introduced into the accumulator in the same manner as in an adding operation.

- 5 Thereafter the selector carriage is returned to the initial position and the value which is to be subtracted is set up in the selector, and the bridges 197, (198) (Fig. 4) are rocked about the studs 196 by means of the rod system 203, 204 and the 10 subtraction key 88' in such a manner that at the following rotation of the main shaft 116 of the machine the toothed wheel 10 is brought into engagement with the toothed sector 2 which has the result that the item now in the selector will 15 be subtracted from the item in the accumulator during the return stroke of the toothed sectors 2.

What we claim is:—

1. In a calculating machine adapted to perform different types of calculation, the combination 20 with a frame, an accumulator and a revolutions counter mounted on supports in said frame, selector mechanism upon which numerical values of a plurality of denominations may be set, a single set of ten number keys for setting values in 25 said selector mechanism, and means operative to transfer to the accumulator a numerical value which may be set on said selector mechanism by the actuation of one or more of said number keys, of control means common to all number keys for 30 initiating the operation of said transfer means and for controlling the number of successive transfers to said accumulator of the numerical value set on said selector mechanism, and calculation controlling means including a setting 35 key for setting said control means for and initiating a single transfer and a second setting key for conditioning said control means for a plurality of transfers in accordance with the type of calculation to be performed, said calculation controlling means including means operable upon 40 the actuation of any one of said number keys to adjust said control means for and to initiate the performance of the number of transfers corresponding to the actuated number key when said number key is actuated following the actuation of 45 said second setting key.

2. In a calculating machine adapted to perform different types of calculation, the combination 50 with a frame, an accumulator and a revolutions counter mounted on supports in said frame, selector mechanism upon which numerical values of a plurality of denominations may be set, a single set of ten number keys for setting values in 55 said selector mechanism, and means operative to transfer to the accumulator a numerical value which may be set on said selector mechanism by the actuation of one or more of said number keys, of control means common to all number keys for initiating the operation of said transfer means 60 and for controlling the number of transfers to said accumulator of the numerical value set on said selector mechanism, adjusting means operable by the actuation of any one of said number keys to adjust said control means for the number 65 of transfers corresponding to the actuated numeral key, said adjusting means being normally inoperative, and setting means including a setting key for rendering said adjusting means operative when the desired type of calculation includes a plurality of transfers.

3. In a calculating machine adapted to perform different types of calculation, the combination 70 with a frame, an accumulator and a revolutions counter mounted on supports in said

frame, selector mechanism upon which numerical values of a plurality of denominations may be set, a single set of ten number keys for setting values in said selector mechanism, and means operative to transfer to the accumulator a numerical value 5 which may be set on said selector mechanism by the actuation of one or more of said number keys, of control means common to all number keys for initiating the operation of said transfer means and for controlling the number of transfers to said 10 accumulator of the numerical value set on said selector mechanism, means for normally locking said control means, and a setting key adapted to release said locking means.

4. In a calculating machine adapted to perform 15 different types of calculation, the combination with a frame, an accumulator and a revolutions counter mounted on supports in said frame, selector mechanism upon which numerical values of a plurality of denominations may be set, a single set of ten number keys for setting values in 20 said selector mechanism, and means operative to transfer to the accumulator a numerical value which may be set on said selector mechanism by the actuation of one or more of said number keys, 25 of control means common to all number keys for initiating the operation of said transfer means and for controlling the number of transfers to said 30 accumulator of the numerical value set on said selector mechanism, means for normally locking 35 said control means, means including a starting key for releasing said locking means to set said control means for a single transfer, setting means for releasing said locking means when a plurality of transfers are desired, said setting means including a setting key, and means operated by the 40 actuation of any one of said numeral keys after actuation of said setting key for setting said control means for the number of transfers corresponding to the actuated number key.

5. In a calculating machine adapted to perform different types of calculation, the combination 45 with a frame, an accumulator and a revolutions counter mounted on supports in said frame, selector mechanism upon which numerical values 50 of a plurality of denominations may be set, a single set of ten number keys for setting values in said selector mechanism, and means operative to transfer to the accumulator a numerical value which may be set on said selector mechanism by the actuation of one or more of said number keys, 55 of control means common to all number keys for initiating the operation of said transfer means and for controlling the number of transfers to said accumulator of the numerical value set on 60 said selector mechanism, setting means adapted to be rendered operative at will when the type of calculation requires a multiple transfer of the set numerical value to the accumulator, and means actuated by each of said number keys when 65 said setting means is rendered operative for adjusting said control means for the number of transfers corresponding to the value of the actuated number key and for initiating operation of 70 said transfer means.

6. A calculating machine as claimed in claim 5, in combination with means operated automatically when said setting means is rendered operative for blocking said transfer means from transferring to said accumulator the numerical values corresponding to such number keys as may be thereafter actuated.

7. A calculating machine as claimed in claim 5, wherein said control means includes a shaft and a plurality of fingers fixed thereto, in different angu- 75

lar adjustments upon the same, said fingers constituting stops which determine the number of transfers to be made by said transfer means, and said number keys actuated means comprises 5 means for rendering that finger operative which corresponds to the actuated number key.

8. A calculating machine as claimed in claim 5, wherein said control means includes a shaft and a plurality of fingers fixed thereto, in different 10 angular adjustments upon the same, said fingers constituting stops which determine the number of transfers to be made by said transfer means, and said number keys actuated means comprises means for rendering that finger operative which 15 corresponds to the actuated number key, in combination with an additional finger on said shaft for adjusting said control means for one transfer, and a setting key operable independently of said number keys for rendering said additional finger 20 operative.

9. In a calculating machine adapted to perform different types of calculation, the combination with a frame, an accumulator and a revolutions counter mounted on supports in said frame, selector mechanism upon which numerical values of a plurality of denominations may be set, a single set of ten number keys for setting values in said selector mechanism, and means operative to transfer to the accumulator a numerical value 25 which may be set on said selector mechanism by the actuation of one or more of said number keys, of control means common to all number keys for initiating the operation of said transfer means and for controlling the number of transfers to 30 said accumulator of the numerical value set on said selector mechanism; said control means comprising a pivotally mounted toothed sector, a spring for turning said sector in one direction, and restoring means periodically actuated by said 40 transfer means for turning said sector in the opposite direction.

10. In a calculating machine adapted to perform different types of calculation, the combination with a frame, an accumulator and a revolutions counter mounted on supports in said frame, selector mechanism upon which numerical values of a plurality of denominations may be set, a single set of ten number keys for setting values in said selector mechanism, and means operative to transfer to the accumulator a numerical value which may be set on said selector mechanism by the actuation of one or more of said number keys, of control means common to all number keys for initiating the operation of said 45 transfer means and for controlling the number of transfers to said accumulator of the numerical value set on said selector mechanism; said control means comprising a pivotally mounted toothed sector, locking means for said sector, 50 spring means for turning said sector in one direction upon release of said locking means, movable means actuated by such turning of said sector to block said selector mechanism, and restoring means periodically actuated by said 55 transfer means for turning said sector in the opposite direction to reset the same.

11. A calculating machine as claimed in claim 10, wherein said transfer means includes a motor-driven shaft, transfer mechanism, and a clutch; 60 for coupling said shaft and transfer mechanism; and said movable means actuates said clutch.

12. A calculating machine as claimed in claim 10, wherein said transfer means includes a motor-driven shaft, transfer mechanism, and a clutch; 65 for coupling said shaft and transfer mechanism;

and said control means includes a motor-switch, said movable means controlling said motor-switch and clutch.

13. In a calculating machine adapted to perform different types of calculation, the combination with a frame, an accumulator and a revolutions counter mounted on supports in said frame, selector mechanism upon which numerical values of a plurality of denominations may be set, a single set of ten number keys for setting values in said selector mechanism, and means operative to transfer to the accumulator a numerical value which may be set on said selector mechanism by the actuation of one or more of said number keys, of control means common to all number keys for 15 initiating the operation of said transfer means and for controlling the number of transfers to said accumulator of the numerical value set on said selector mechanism, said transfer means including a main shaft and transfer mechanism 20 actuated thereby to transfer the set value to said accumulator once for each rotation of said shaft; said control means comprising a pivotally mounted toothed sector, spring means for turning said sector in one direction to initiate the operation 25 of said transfer means, a bell crank lever carrying a restoring pawl for actuating said toothed sector in the opposite direction, and a disk carrying cam means for actuating said bell crank, said disk being fixed to said main shaft of the transfer 30 means.

14. A calculating machine as claimed in claim 13, wherein said restoring pawl is mounted on one arm of said lever to form a toggle mechanism, and spring means normally retains said pawl out 35 of the path of movement of said toothed sector, the rocking of said lever by said cam means flattening said toggle mechanism to carry said pawl into engagement with said toothed sector.

15. In a calculating machine adapted to perform different types of calculation, the combination with a frame, an accumulator and a revolutions counter mounted on supports in said frame, selector mechanism upon which numerical values of a plurality of denominations may be set, a single set of ten number keys for setting values in said selector mechanism, and means operative to transfer to the accumulator a numerical value which may be set on said selector mechanism by the actuation of one or more of said number keys, 45 of control means common to all number keys for initiating the operation of said transfer means and for controlling the number of transfers to said accumulator of the numerical value set on said selector mechanism; said control means comprising a pivotally mounted toothed sector, a releasable locking means for said sector, a spring for turning said sector in one direction when said locking means is released, a releasing device for said locking means, a bridge and means to condition the same for displacement upon the actuation of any one of said numeral keys, and a pin and slot connection between said bridge and said releasing means.

16. In a calculating machine adapted to perform different types of calculation, the combination with a frame, an accumulator and a revolutions counter mounted on supports in said frame, selector mechanism upon which numerical values of a plurality of denominations may be set, a single set of ten number keys for setting values in said selector mechanism, and means operative to transfer to the accumulator a numerical value which may be set on said selector mechanism by the actuation of one or more of said number 75

keys, of control means common to all number keys for initiating the operation of said transfer means and for controlling the number of transfers to said accumulator of the numerical value 5 set on said selector mechanism; said control means comprising a pivotally mounted toothed sector, a releasable locking means for said sector, a spring for turning said sector in one direction when said locking means is released, a lever 10 carrying a releasing device adapted to cooperate with said locking means, spring actuated means normally retaining said lever in inoperative position to prevent engagement of said releasing device and said locking means, setting means including a manual setting key for moving said lever into operative position to carry said releasing device into proximity to said locking means, a bridge adapted to be displaced upon the actuation of any one of said numeral keys, and 15 a pin and slot connection between said bridge and said releasing means.

17. A calculating machine as claimed in claim 16, in combination with means carried by the "naught" key of said set of number keys for displacing said lever into inoperative position upon actuation of said "naught" key following a movement of said lever into operative position by said setting means.

18. In a calculating machine having an accumulator, a ten key item set up mechanism, ten item keys, and means to transfer the items set up to the accumulator; mechanism for controlling the number of transfer operations from said item set up mechanism to said accumulator, 30 said control mechanism comprising a toothed member, a locking pawl and a restoring pawl for cooperation with the toothed member, said locking pawl normally engaging said toothed member to retain the same in inoperative position, 35 spring means for moving said member upon the release of said locking pawl, a key and setting means actuated thereby to release said locking pawl and to limit the movement of said toothed member to a displacement corresponding to the pitch of one tooth, retaining means operative 40 only when said toothed member is moved to retain said setting means in actuated position, means actuated by the movement of said toothed member to initiate operation of the transfer 45 means, and means operated by said transfer means to actuate said restoring pawl to restore said toothed member to its normal inoperative position, whereby said retaining means is rendered inoperative, thereby releasing said setting 50 means to restore said locking pawl to operative position.

19. In a calculating machine having an accumulator, a ten key item set up mechanism, ten item keys, and means to transfer the items set 55 up to the accumulator; mechanism for controlling the number of transfer operations from said item set up mechanism to said accumulator, said control mechanism comprising a toothed member, a locking pawl and a restoring pawl for cooperation with the toothed member, said locking pawl normally engaging said toothed member to retain the same in inoperative position, spring 60 means for moving said member upon the release of said locking pawl, a control key and means actuated thereby to move a releasing device into 65 operative position, means operative upon the actuation of any significant item key to operate said releasing device to release said locking pawl and to limit the displacement of said toothed member to a displacement equal to the number 70

of teeth corresponding to the actuated item key, means operated by the movement of said toothed member to initiate operation of the transfer means, means actuated by an element of the transfer means to operate said restoring pawl to effect a one-tooth return movement of said toothed member for each operation of said transfer means corresponding to one transfer of the set numerical value to said accumulator, whereby said toothed member is restored to inoperative 10 position upon the completion of a number of transfers corresponding to the actuated item key. 5

20. In a calculating machine having an accumulator, a ten key item set up mechanism, ten item keys, and means to transfer the items set up to the accumulator; mechanism for controlling the number of transfer operations from said item set up mechanism to said accumulator, said control mechanism comprising a toothed member, a locking pawl and a restoring pawl 15 for cooperation with the toothed member, said locking pawl normally engaging said toothed member to retain the same in inoperative position, spring means for moving said member upon the release of said locking pawl, a lever carrying 20 a releasing device, key-actuated means for moving said lever to bring said releasing device into operative position with respect to said locking pawl, means thereupon operative upon the actuation of any significant item key to operate said 25 releasing device to release said locking pawl and to limit the displacement of said toothed member to a displacement equal to the number of teeth corresponding to the value of actuated item key, means operated by the movement of said toothed member to initiate operation of the transfer means, means actuated by an element of the transfer means to operate said restoring pawl to effect a one-tooth return movement of said toothed member for each operation of said transfer 30 means corresponding to one transfer of the set numerical value to said accumulator and to periodically actuate said lever to move said retaining means into an inoperative position, thereby to cooperate with said restoring pawl to 35 effect a step-by-step return of said toothed member into inoperative position. 40

21. In a calculating machine, control mechanism as claimed in claim 20, wherein said toothed member is an arcuate sector fixed to a pivotally 45 mounted shaft.

22. In a calculating machine, an accumulator, a selector mechanism and ten number keys for setting a desired numerical value on said selector mechanism, transfer means for transferring to said accumulator a numeral value set on said selector mechanism, said transfer means comprising transfer mechanism having a main shaft adapted to be connected by a clutch to an operating shaft, and control means for actuating said clutch in accordance with the desired number of transfers of the set numerical value; said control means including a pivotally mounted toothed sector, a member actuated thereby, and a three armed lever actuated by said member, one arm of 55 said lever controlling said clutch to engage the same upon a displacement of said toothed sector to actuate said member and thereby said lever. 60

23. In a calculating machine, an accumulator, a selector mechanism and ten number keys for setting a desired numerical value on said selector mechanism, transfer means for transferring to said accumulator a numeral value set on said selector mechanism, said transfer means comprising transfer mechanism having a main shaft 70

75

adapted to be connected by a clutch to an operating shaft, and control means for actuating said clutch in accordance with the desired number of transfers of the set numerical value; said control means including a pivotally mounted toothed sector, locking means normally retaining said sector in inoperative position, a spring for moving said sector into operative position upon release of said locking means, key actuated means for releasing 10 said locking means, and means for retaining said key actuated means in actuated position so long as said sector is displaced from inoperative position.

24. In a calculating machine, an accumulator, a selector mechanism and ten number keys for setting a desired numerical value on said selector mechanism, transfer means for transferring to said accumulator a numeral value set on said selector mechanism, said transfer means comprising transfer mechanism having a main shaft adapted to be connected by a clutch to an operating shaft, and control means for actuating said clutch in accordance with the desired number of transfers of the set numerical value; said control 20 means including a pivotally mounted toothed sector, locking means normally retaining said sector in inoperative position, a spring for moving said sector into operative position upon release of said locking means, means operable manually into 25 position for actuation by any one of said number keys to release said locking means, and means operative upon the movement of said sector when said locking means is released for locking the actuated key in actuated position and for preventing actuation of any other key so long as said 30 sector is displaced from inoperative position.

25. In a calculating machine, an accumulator, a selector mechanism and ten number keys for setting a desired numerical value on said selector 40 mechanism, transfer means for transferring to said accumulator a numeral value set on said selector mechanism, said transfer means comprising transfer mechanism having a main shaft adapted to be connected by a clutch to an operating shaft, and control means for actuating said clutch in accordance with the desired number of transfers of the set numerical value; said control 45 means including a pivotally mounted toothed sector, locking means normally retaining said sector in inoperative position, a spring for moving said sector into operative position upon release of said locking means, a starting key, means operable by one of said keys for releasing said locking means, 50 a bell crank lever pivoted for movement about the axis of said toothed sector, means carried by one arm of said lever for preventing actuation of any of said keys so long as said toothed sector is displaced from inoperative position, a second lever for controlling said clutch, and a one-way connection 55 between the second arm of said first lever and an arm of said second lever.

26. In a calculating machine adapted to perform different types of calculation, the combination with a frame, an accumulator and a revolutions counter mounted on fixed supports in said frame, a multiple denomination selector mechanism including a single set of ten numeral keys, means for transferring to said accumulator a numerical value which is set upon said selector 65 mechanism by actuation of said numeral keys, means operable after a first numerical value has been set to prevent the transfer to said accumulator of a further numerical value which may be thereafter set upon said selector mechanism by 70 one of said numeral keys, and control means

operable by the setting of said further numerical value by one of said keys to effect the transfer to said accumulator of a total value equal to a multiple of the first numerical value set upon said selector mechanism.

27. A calculating machine as claimed in claim 26, in combination with means for registering upon said revolutions counter the said further numerical value set by one of said keys.

28. A calculating machine as claimed in claim 10 26, in combination with means for determining the sense in which said first numerical value is transferred to said accumulator.

29. In a calculating machine adapted to perform different types of calculation, the combination with a frame, an accumulator and a revolutions counter mounted on fixed supports in said frame, a multiple denomination selector mechanism including a single set of ten numeral keys, means for transferring to said accumulator a 20 numerical value which is set upon said selector mechanism by actuation of said numeral keys, means operable after a first numerical value has been set to prevent the transfer to said accumulator of a further numerical value which may be 25 thereafter set upon said selector mechanism by one of said numeral keys, and control means operable by the setting of said further numerical value by one of said keys to effect the transfer to said accumulator of a total value equal to the product 30 of the first and the further numerical value set upon said selector mechanism.

30. A calculating machine as claimed in claim 26, wherein said transfer means includes members cooperating with said selector mechanism for 35 actuating said accumulator by increments corresponding to the numerical values set in the several denominations of said selector mechanism, and said preventing means includes a rock shaft, a setting key for rocking said rock shaft, and 40 means carried by said rock shaft for displacement into position to prevent actuation of certain of said members in accordance with the setting of said selector mechanism.

31. In a calculating machine, an accumulator, 45 a selector mechanism upon which a numerical value may be set, means for transferring the set numerical value to said accumulator, and control means for said transfer means; said selector mechanism comprising a carriage having a plurality of columns of ten value members, a single set of ten number keys for selectively actuating the desired value member of one of said columns, means for advancing said carriage to bring an adjacent column of value members into cooperative 50 relation to said number keys, whereby a multiple-denomination numerical value may be set upon said selector mechanism by the successive actuation of the number keys; said transfer means including a movable calculating member 55 for each denomination of said selector mechanism, the actuated value members serving as stops to limit the movement of said calculating members, and means actuated in accordance with the degree of movement of said calculating members to transfer to said accumulator the numerical value set upon said selector mechanism; and said control means includes blocking means operable to prevent movement of the calculating members cooperating with those columns of value 60 members in which no member has been actuated by said number keys.

32. A calculating machine as claimed in claim 31, wherein said calculating members are notched, and said blocking means comprises a rail adapted 75

to be engaged in the notches to block movement of the calculating members.

33. A calculating machine as claimed in claim 31, wherein said control means includes means operated upon the actuation of a number key, subsequent to a movement of the blocking means to operative position, for energizing said transfer means to transfer to said accumulator the numerical value originally set upon said selector mechanism when said blocking means was inoperative and to repeat said transfer until the number thereof corresponds to the said subsequently actuated number key.

34. A calculating machine as claimed in claim 31, wherein said control means includes means operated upon the actuation of a number key, subsequent to movement of the blocking means to operative position, for energizing said transfer means to transfer to said accumulator the numerical value originally set upon said selector mechanism when said blocking means was inoperative and to repeat said transfer until the number thereof corresponds to the said subsequently actuated number key, means operative upon the completion of said number of transfers to move said selector mechanism carriage to displace the originally set numerical value to an

adjacent denominational order, whereby the subsequent actuation of a number key will effect a transfer of the originally set numerical value to said accumulator a number of times corresponding to the actuated number key and the changed 5 denominational order.

35. A calculating machine as claimed in claim 31, wherein said control means includes means operated upon the actuation of a number key, subsequent to a movement of the blocking means to operative position, for energizing said transfer means to transfer to said accumulator the numerical value originally set upon said selector mechanism when said blocking means was inoperative and to repeat said transfer until the 15 number thereof corresponds to the said subsequently actuated number key; in combination with a revolutions counter, normally inoperative means adapted to transfer to said revolutions counter a numerical value corresponding to an 20 actuated number key, and means for rendering said last means operative simultaneously with the movement of said blocking means into operative position.
